UNITED STATES PATENT OFFICE.

WALTER RICHARDSON, OF NEW YORK, N. Y., ASSIGNOR TO HENRY TRENCHARD, JR., OF BROOKLYN, NEW YORK.

APPARATUS FOR APPLYING FASTENINGS TO ENVELOPS, &c.

1,286,414.

Specification of Letters Patent.

Patented Dec. 3, 1918.

Original application filed May 10, 1916, Serial No. 96,693. Divided and this application filed October 9, 1916. Serial No. 124,452.

To all whom it may concern:

Be it known that I, WALTER RICHARDSON, a citizen of the United States, and a resident of the borough of Manhattan, city, county, and State of New York, have invented certain new and useful Improvements in Apparatus for Applying Fastenings to Envelops, &c., of which the following is a specification.

10 My improvements relate to means for equipping commercial packages, envelops, and the like, with fastening devices of the class in which a pronged eyelet clasp on the receptacle part is used in conjunction with a perforation formed for its reception on the flap to secure the latter in closed relationship to said receptacle part in a manner now well known in the art.

This application is a division of that filed 20 by me May 10, 1916, Serial No. 96,693, in which provision is made for simultaneously applying the clasp, reinforcing the flap perforation by "patches" and making an imprint on the latter. The present invention 25 relates exclusively to the means for feeding and applying the pronged eyelet clasp to the receptacle portion of the envelop or similar package, and consists in the specific construction and arrangement of parts described 30 and claimed herein, whereby the pronged eyelet clasps are selected and fed automatically to eyelet-upsetting mechanism of peculiar construction, all as hereinafter more fully set forth.

35 In the accompanying drawings,

Figure 1, is a front elevation of the apparatus;

Fig. 2, is an end elevation thereof;

Fig. 3, is a plan thereof;

40 Fig. 4, is what may be designated as a front view of the feed hopper, channel, etc., as they are positioned in the machine so that the open face of the feed channel is in full view of the operator;

45 Fig. 5, is an elevation, partly in section, taken at right angles to Fig. 4;

Fig. 6, is a transverse section taken upon plane of line 6—6, Fig. 5;

50 Fig. 7, is a perspective view of one of the relief gates provided at the lower end of the feed channel;

Fig. 8, is a perspective view of the feed check lever or gate escapement;

Fig. 9, a view upon a larger scale of the lower part of the feed channel partly broken away and in section to show the operation 55 of the feed check or escapement;

Fig. 10, is a transverse section taken upon plane of line 10—10, Fig. 9;

Fig. 11, is a perspective view of the clip 60 rest at the bottom of the feed channel;

Fig. 12, is a rear or inside view of the rotatable feed hopper, the feed channel being shown in dotted lines;

Fig. 13, is a horizontal sectional elevation 65 taken upon plane of line 13—13, Fig. 4;

Fig. 14, is an elevation on a larger scale of the inner face of the hopper plate, the rotatable hopper being omitted;

Fig. 15, is a perspective view of the hopper 70 return guard;

Fig. 16, is a top view of the feed hopper, etc.;

Fig. 17, is a horizontal section taken upon line 17—17, Fig. 14, but on a smaller scale; 75

Fig. 18, is a perspective view of the adjustable foot or bracket on which the feed channel standard is supported;

Fig. 19, is a perspective view of the adjustable bearing for the outer end of the rotatable feed hopper shaft; 80

Fig. 20, is a plan of the operative parts which act directly upon the envelop;

Figs. 21, and 22, are sectional elevations illustrating in detail the clip applying mechanism and the operation thereof; 85

Fig. 23, is a perspective view of a two prong clip fastening before application to the body portion of an envelop;

Fig. 24, is a sectional view of a portion of 90 an envelop body and clip applied thereto;

Fig. 25, is an elevation, partly in section, of the power clutch mechanism;

Fig. 26, is a transverse section upon plane of line 26—26, Fig. 25; 95

Fig. 27, is a detail view of the cam portion of the clutch sleeve;

Fig. 28, is a sectional detail upon a larger scale of certain parts of the eyelet-riveting punch; 100

Fig. 29, is a sectional detail taken upon plane of line 29—29, Fig. 21, showing means

for effecting the lateral horizontal adjustment of the eyelet-riveting punch;

Fig. 30, is a perspective view of the open end of an envelop after treatment by my apparatus;

Fig. 31, is a view like unto Fig. 9, on the same sheet of drawings, showing the reverse position of the clip escapement and the release doors open, the latter having been omitted from Fig. 9, except as indicated therein in dotted lines.

In the drawings a , a' , represent the basic frame or table of the machine supported on legs a' , a' . Looking from the front of the apparatus, as in Fig. 1, the cam shaft C, may be said to extend transversely across the table a , being mounted in bearings a^2 , a^3 , and being held against longitudinal movement by the cams C' , C^2 , which abut against the inner sides of said bearings a^2 , a^3 , and act, in this respect, as retaining collars on the cam shaft C, for the purpose designated.

Upon the right extremity of the cam shaft C, is loosely mounted a power pulley P, the hub of which is formed with an annular groove p , within which rests a detent c , mounted upon a collar c' , rigidly secured on the end of the shaft C. Thus the detent c , allows the power pulley P, to rotate freely on the shaft C, while holding it against longitudinal movement thereon.

Splined to the shaft C, as shown in Fig. 26, so as to be slidable thereon longitudinally between the right hand bearing a^2 , and the power pulley P, is the clutch sleeve c^4 , formed with jaw teeth c^5 , for engagement with corresponding jaw teeth p' , on the left hand side of the hub of the power pulley P. In Fig. 25, to which reference may be had for a clear understanding of the power clutch mechanism, the jaw teeth c^5 , and p' , are shown in solid lines as out of engagement because the clutch sleeve c^4 , is retracted against the resistance of the compressible spring c^6 , which is seated in a recess formed for its reception in the lower part of the journal bearing a^3 , and which tends constantly, by its action on the plunger c^7 , to thrust the clutch sleeve c^4 , into engagement with the hub of the power pulley P, to thereby rotate the cam shaft C. The clutch sleeve c^4 , is held in its retracted position by a spring latch or bolt b , which engages normally with an annular shoulder c^{41} , on the clutch sleeve c^4 , but which, when withdrawn by the depression of the foot pedal or tread B, acting through the medium of the connecting rod b' , and rock lever b^2 , (against the resistance of the retractile spring b^3 , see Fig. 2) on which the bolt b , is mounted, releases the clutch sleeve to the impulse of the compression spring c^6 . When the foot pedal B, is released the spring b^3 , returns the treadle and connections to normal position

with the bolt b , (which may be in the form of a roller) again protruding into the path of the cam portion c^{42} , of the clutch sleeve shoulder c^{41} , so that by its continued rotation with the shaft C, the cam sleeve c^4 , will force itself out of engagement with the hub of the power pulley P, thereby releasing the cam shaft C, until the treadle is again depressed to release the clutch sleeve and effect another cycle of operation,—it being understood of course, that the apparatus is practically at rest while a finished envelop is being removed and another substituted, and that the treadle B, is depressed only when a new envelop is in position for treatment. When at rest in normal position the bolt b , contacts with a shoulder c^{43} , adjacent to the apex of the cam portion c^{42} , of the clutch sleeve c^4 , as shown in Fig. 27.

The left end of the cam shaft C, is provided with a hand wheel c^8 , to facilitate the turning and manipulation of the shaft and cams for any reason when the clutch sleeve c^4 , is not in engagement with the hub of the power pulley P, as for the purposes of inspection, cleaning dies, etc. In such case the clutch sleeve c^4 , is positively held out of engagement with the hub of the power pulley by a cotter pin c^9 , inserted through a hole c^{10} , drilled in the clutch sleeve c^4 , and into engagement with a hole c'' , in the cam shaft C, as shown in Fig. 26, or by any other mechanical expedient.

The hand wheel c^8 , is made of such weight and proportion as also to act as a fly wheel to steady and complete the rotation of the cam shaft.

The cams C' , C^2 , C^3 , are rigidly attached to the shaft C. Cam C' , actuates, through the medium of the cam lever D' , the inner patch die I, and the clip eyelet "rivet" punch R; the cam C^2 , actuates, through the medium of the cam lever D^2 , the outer patch die K, and the imprint or type die attached thereto; while the cam C^3 , actuates, through the medium of the cam lever D^3 , the ejector punch, which punches the central clip hole through both reinforcing patches and through the envelop flap after they are applied thereto, and then effects the ejection of this central waste through the inner patch die I, as set forth in my concurrent application hereinbefore referred to. The cam levers D' , D^2 , D^3 , are of the second order, being fulcrumed to the table a , at their rear extremities, as at d' , d^2 , d^3 , the power being applied to their medially positioned cam pins which protrude into the respective grooves of the cams C' , C^2 , C^3 , and being transmitted by the outer or front ends of said cam levers, as above intimated, to the patch dies I, K, printing plunger N, and punches connected therewith. A fourth cam C^4 , also rigidly attached to the cam shaft C,

is the patch strip feed cam which actuates the mechanism by which the patch strips s' , s^2 , are drawn through the apparatus.

The bifurcated forward end of the cam lever D' , straddles the hollow patch die tube I , which is mounted slidably in the bearings i' , and i^2 , both of which, in the construction shown in the drawings, form part of the table bracket i , secured to rigid extensions a^{21} , and a^{22} , of the table or base a . The said forward end of the cam lever D' , rests between a collar i^3 , and a lateral extension arm i^4 , both of which are rigidly attached to the die tube I .

15 The support for the anvil o , for the clip "riveting" or eyelet punch r^* , is formed by a forward extension of the die plate j' , which is secured to the outer side of the bearing block i^2 , forming part of the bracket i , on 20 which the die tube I , is mounted. The means of securing the pronged and eyeleted clip t , shown in Fig. 23, to the envelop body f' , will be understood most readily by referring to Fig. 21, which shows the relative positions of 25 parts prior to the riveting action, and to Fig. 22, which illustrates the latter.

The eyelet riveting punch R , considered as a whole, is rigidly mounted on the extension arm i^4 , heretofore described as rigidly attached to the die tube I . Its operative end or shank r , is further centralized and supported by passing through a bearing plate w^2 , (Figs. 21 and 22) secured rigidly to the back of the lower extremity of the channel 30 standard U , which at this point is formed with a recess u^4 , extending through it into which the shank r , of the punch R , protrudes when advanced as shown in Fig. 22. The punch proper, r^* , is tubular, and preferably 35 formed by inserting a tube r^* , in the drilled end of the shank r , as shown in detail in Fig. 28, an axial recess r' , of less diameter than the punch tube r^* , being also drilled in the shank r , for the compressible spring r^2 , 40 which bears upon the head r^3 , of the centralizing pin r^4 . The diameters of the bore of the punch tube r^* and of the centralizing pin r^4 , which fits it are less than that of the spring recess r' , so that the inner end of the 45 punch tube r^* , forms a shoulder against which the head r^3 , of the centralizing pin r^4 , is held normally by the spring r^2 , said head being of nearly the same diameter as that of the spring recess r' . The function of the 50 centralizing pin r^4 , is to support, forward and present the lowest clip t , in the feed channel u , to the upsetting die o' , of the anvil o , during the work thrust of the punch R . This it does by entering the eyelet of the clip 55 t , and supporting the latter until the end of the centralizing pin r^4 , contacts with the upsetting anvil o' , when the continued advance of the punch R , causes the compression spring r^2 , to yield to said pin r^4 , and allow

the end of the punch tube r^* , to push the 65 eyelet of the clip through the portion f' , of the body of the envelop and against the upsetting anvil o' , as illustrated in Fig. 22, and with the result shown in Fig. 24, in a manner well known in the art.

The punch R , may itself be made laterally adjustable and horizontally adjustable upon its supporting arm i^4 , by resort to any desired or well known mechanical expedient, so that I do not limit myself in this respect, 75 the main object being to furnish means whereby both punch R , and feed channel standard U , may be adjusted alike in position as related to each other and as related to the relatively fixed axial positions of the 80 dies and punch I , K , and R . As shown in the drawings by way of illustration, referring particularly to Figs. 21, 22, and 29, the punch R , is mounted in a split box z , positioned in a longitudinal rectangular slot i^{44} , 85 formed for it in said supporting arm i^4 , which is also provided with binding screws z' , z^2 , arranged to contact with the upper half of the box z , at any position to which the box may be adjusted in said longitudinal 90 slot i^{44} . The binding screws z' , z^2 , are designed to secure the punch R , rigidly to the supporting arm i^4 . i^6 , is a collar upon the punch R , which facilitates the positioning of the punch accurately upon the arm i^4 , as 95 related to the channel standard U .

The fastening clips t , are fed to the rivet punch R , through the channel u , into the upper end of which they are fed by the rotatable conical portion of the hopper V , 100 mounted upon a shaft V' , which is journaled in a bearing u' , supported upon the upper end of the channel standard U , and in a bearing v , on the upper end of the standard V^2 . The bearing v , is made adjustable horizontally, toward or from the front of the machine, upon the top of its standard V^2 , by any suitable means, as by slots v' , v^2 , and screw bolts v^2 , v^2 , as shown in Figs. 16, and 105 19; and the channel standard U , is made correspondingly adjustable by being mounted near its lower extremity upon a foot piece U' , formed with an elongated slot u^2 , through which a bolt u^3 , passes to secure the foot piece U' , and standard U , adjustably 110 to the upper side of the bearing i^2 , on the bracket i . The positions of the foot piece U' , and channel standard U , are indicated in dotted lines in Fig. 20.

The object of provision for the horizontal 115 adjustment of the eyelet-riveting punch R , and the channel standard U , and bearing v , on the standard V^2 , is to provide for the changing of these parts with relation to the patch dies I , and K , to compensate for variations in length of the envelop flaps to the bodies of which the clip fastenings are to be applied.

The bearing u' , for the inner end of the feed shaft V' , is formed in a plate V^3 , attached to the upper end of the channel standard U , said plate V^3 , being formed with a flat vertical surface v^3 , facing the inner side of the rotatable portion V , of the feed hopper, and with the receiving hopper v^4 , into and through which the clips are dumped into said rotatable hopper V , as will be understood by reference more particularly to Fig. 5.

This figure, as well as Fig. 13, show the manner in which the rotatable portion V , of the hopper is yieldably mounted on the inner end of the shaft V' . That is to say said portion V , is not secured to its shaft V' , to rotate positively therewith under all conditions, so that, in the event of a clog or jam in the feed between the face plate V^3 , and said rotatable portion V , of the hopper the latter will cease to rotate with its shaft V' , thereby obviating damage. This result is attained by mounting the hub v^5 , of the rotatable portion V , on a portion v^6 , of the shaft V' , formed with a shoulder v^7 , against which the hub v^5 , is pressed normally by a spring v^8 , held in position on the threaded end v^9 , of the shaft V' , by a thumb nut v^{10} , so as to be compressible more or less tightly against the outer face of the said rotatable conical section V , of the hopper. Hence, obviously, said section V , is held to rotate with its shaft V' , only by the frictional resistance afforded by the elastic resilient pressure of said spring v^8 , so that when the resistance to rotation with the shaft V , encountered by the conical part V , is greater than the frictional resistance exerted by the spring v^8 , the otherwise rotatable conical part V , will be held stationary with the face plate V^3 , and consequently the portion v^6 , of the shaft V' , will simply slip around within the hub v^5 , of said conical part V . Under such conditions it is needless to say that the conical section V , may be readily loosened upon the shaft V' , or possibly removed, so that the cause of obstruction may be quickly ascertained and remedied without danger of injury to any part of the apparatus, and without delay or serious loss of time.

The feed shaft V' , is held against longitudinal movement by its shoulder v'' , resting against one side of the bearing u' , and by a collar v^{12} , secured to the shaft V' , and resting against the other side of said bearing u' , as shown in Figs. 5, and 13. A fixed pulley v^{13} , on the shaft V' , affords means whereby the conical section V , of the hopper may be continuously rotated at a moderate speed.

While I have thus provided as above set forth for any unforeseen obstruction to the operation of the feed hopper I reduce dan-

ger thereof to the minimum degree by my means for, and method of, feeding the eyelet clips to the delivery channel u .

By reference to Fig. 12, it will be seen that the inner edge of the conical section V , of the feed hopper is formed with a series of equi-distant inclined slots v^{14} , the open sides of which are opposed to the flat vertical surface v^3 , of the face plate V^3 . The shoulder v^7 , on the shaft V' , holds the rotatable section V , so that its slotted edge is positioned, say, one sixteenth of an inch (less than the depth of the eyelets but greater than the thickness of the prongs) from said opposed surface v^3 , of the face plate V^3 , thus creating an annular space v^{15} , between them sufficient to accommodate the prongs of the clips t , but not sufficient to admit the eyelets of the clips, which however are free to enter the slots v^{14} . As a result of this construction the rotation of the conical section V , causes some of the clips to enter the space v^{15} , with their eyelets projecting into the slots v^{14} , and to be carried around to the mouth u^5 , of the channel u , said mouth u^5 , being formed in the face of the plate V^3 , as indicated in dotted lines in Fig. 12, and shown in solid lines in Fig. 14, by reference to which latter, and to Fig. 13, it will be seen that the mouth u^5 , of the channel is also formed with overlapping edges u^6 , u^8 , which are continuations of those on the channel u , shown in cross section in Fig. 6.

The clips thus forwarded in the direction of the arrow, Fig. 12, drop into the mouth u^5 , of the channel u , if there is room therein, otherwise they are carried over, controlled by the overlapping edge u^{11} , (see Fig. 14) to the deflector v^{16} , by which they are shunted back into the mouth v^4 , of the hopper to be returned thereby to the rotatable section V .

The eyelets are supported in the channel u , until required for use, by the check or escapement lever u^7 , which is of the rock lever class, pivotally supported at u^8 , on the channel standard U , and is formed with points u^9 , u^{10} , which contact alternately with the eyelets of the clips as they are checked off to the lower part of the channel. When at rest in normal position as shown in Fig. 9, the upper arm u'' of the escapement lever u^7 , rests against the side of the channel standard U , while when rocked over into the position shown in Fig. 31, its lower arm u^{11} , bears against said channel standard U . The point u^9 , sustains the column of clips in the channel u , above, as in Fig. 9, until rocked back into the position shown in Fig. 31, when the point u^{10} , sustains the column of clips temporarily until returned to normal position as in Fig. 9, such return allowing the lowest clip to drop to its seat below,

while the point u^9 , intercepts the next succeeding clip and thereby again sustains the column of clips above.

The released clip descends from the escapement to a seat u^{12} , at the bottom of the channel u . This seat u^{13} , may be formed directly in the channel standard U , or may be formed of a separate piece u^{14} , to be attached rigidly thereto, as may be found most expedient. The seat u^{13} , positions the clip with its eyelet in alignment with the centralizing pin r^4 , of the eyelet-riveting punch R . The eyelet is held in position on the seat u^{13} , by the front edges of the gates u^{15} , which overlap the eyelet flange and prevent the clip from displacement until forwarded by the riveting punch R , as hereinbefore fully set forth, under the action of which punch the gates yield, being closed normally by springs u^{16} , u^{16} ,—said gates u^{15} , u^{16} , being of course pivotally attached to the lower end of the channel standard U , as at u^{17} , u^{17} . The gates u^{15} , u^{16} , are also provided with rear projections or handles u^{18} , u^{18} , by which they may be manually manipulated when access is desired to the seat u^{13} , to remove a defective clip, or to empty the channel for any reason,—the escapement lever u^7 being also in like manner preferably provided with a handle or projection u^{11} , by which it may be manually manipulated for the latter purpose.

To provide for this manual manipulation of the escapement u^7 , when desired, and also to obviate possibility of damage by the use of rigid positive means of operation, I connect said escapement lever u^7 , with the cam lever D^4 , by means of a coiled spring u^{19} , attached to an extension d^{62} , on said cam lever D^4 , and to the upper arm u'' , of the escapement lever u^7 , as indicated in Fig. 10. Thus when the cam lever D^4 , is in its raised normal position as shown in solid lines in said figure the spring u^{19} , holds the escapement lever u^7 , with its upper arm u'' , against the channel standard U , as in Fig. 9, and when it is lowered as in dotted lines in Fig. 9, it depresses the said escapement lever u^7 , onto the position shown in Fig. 31, with its arm u^{12} in contact with the channel standard. This elastic resilient connection between the escapement and its actuating cam lever is amply sufficient to operate the escapement without danger to the delicate clips, while admitting also of the manipulation of the escapement by hand when desirable, as is frequently the case in the operation of the machine on account of the presence of defective clips in the channel u .

In this connection it may be stated that the channel standard U , is so positioned with relation to the operator, that the clips in the channel u , are always exposed con-

veniently within the line of vision of said operator so that defective clips may be removed, or other precautions taken to prevent damage or delay. This is an important practical advantage in the operation of the machine in order to attain the best results therewith.

The operative use of the apparatus is as follows:

The eyelet riveting punch mechanism having been adjusted to a position in front of the hole punching and patching mechanism at which the axial distance between the two mechanisms is equal to the proper requisite distance between the eyelet clip applied to the body of the envelop and the reinforced prong hole formed for the reception of its prongs on the flap thereof, and the work table W , in a horizontal position, having been vertically adjusted to accommodate the width of the envelop, the treadle is then depressed to release the clutch sleeve on the cam shaft, allowing it to engage with the power pulley to rotate the cam shaft. The treadle being immediately released, the cam shaft will make one revolution and then again come to rest for reasons hereinbefore set forth. During this revolution of the cam shaft a cycle of actions by the several mechanisms take place; *i. e.*, the patch dies remove a circular patch from each patch strip and press them against opposite sides of the envelop flap, and the imprint die acts on the ink ribbon to make the imprint for the next envelop, when the perforating die immediately thereafter punches the central prong opening through both patches and the envelop flap, forcing the severed wad into the discharge passage in the left hand patch die tube. Simultaneously the eyelet riveting punch has advanced, taken up the eyelet clip at the bottom of the feed channel, and forced its eyelet through the opposed portion of the envelop body and against the upsetting die, which turns over and clenches the edges of the eyelet. After the punching of the prong hole in the flap and patches as above stated the patch and print dies and the hole punch retire, when the forwarding cam raises its lever and with it the pawl which rotates the ratchet connected with the strip feed rolls thereby drawing the patch strips into position for the next reciprocation of the patch dies and punch. As the forwarding cam lever is allowed to resume its normal position during the completion of rotation of the said cam, said lever by its connection with the escapement lever on the clip feed channel rocks said escapement so as to check off and release the next succeeding clip in the channel and allow it to descend into position for the next operative stroke of the eyelet-riveting punch.

- The machine being now again at rest at the completion of this single revolution of the cam shaft, since the clutch sleeve has automatically detached itself from the power pulley, and the detent lever has again engaged with its notch or depression in the strip forwarding cam (or in fact as soon as the retractile stroke of the dies and punches has begun) the operation of the apparatus may be conducted continuously though intermittently, in that the treadle may be depressed practically as fast as a completed envelop can be withdrawn and another substituted.
- 15 Incidentally it may be noted that by my special clip eyelet riveting means the eyelet is made to penetrate through the envelop body without previous or preparatory puncture thereof, a saving of what has 20 heretofore constituted a separate operation.

What I claim as my invention and desire to secure by Letters Patent, is:

1. In apparatus of the character designated, in combination, means for applying 25 a pronged-eyelet clip to the body of an envelop, a channel for feeding clips to said clip applying mechanism, and means for adjusting said feed channel horizontally with relation to said clip-applying mechanism, 30 for the purpose described.
2. In apparatus of the character designated, in combination, means for applying a pronged-eyelet clip to the body of an envelop, comprising eyelet riveting mechanism, eyelet clip feed mechanism consisting of a channel for delivering eyelet clips to 35 said eyelet riveting mechanism, and escapement mechanism arranged in connection therewith to cut off and deliver the lowest 40 clip in the channel while supporting those above, said escapement comprising a two pointed check lever which is oscillated automatically through the medium of an elastic resilient connection with a positively operated 45 part of the apparatus, and which also may be operated manually without interfering with the normal operation of the apparatus.
3. In apparatus of the character designated, in combination, means for applying 50 a pronged-eyelet clip to the body of an envelop, comprising eyelet riveting mechanism, eyelet clip feed mechanism consisting of a channel for delivering eyelet clips to 55 said riveting mechanism, and escapement mechanism arranged in connection therewith to cut off and deliver the lowest clip in the channel while supporting those above, said escapement comprising a two pointed 60 check lever which is oscillated automatically through the medium of an elastic resilient connection with a cam-actuated lever, and which also may be operated manually with-

out interfering with the normal operation of the apparatus.

4. In apparatus of the character designated, in combination, means for applying a pronged eyelet clip to the body of an envelop, comprising eyelet riveting mechanism, eyelet clip feed mechanism consisting of a channel for delivering eyelet clips to 70 said riveting mechanism, and escapement mechanism arranged in connection therewith to cut off and deliver the lowest clip in the channel while supporting 75 those above, said escapement comprising a two pointed check lever which is oscillated automatically through the medium of an elastic resilient connection with a cam-actuated lever which also operates other 80 mechanism forming part of the apparatus, and which also may be operated manually without interfering with the normal operation of the apparatus.

5. In apparatus of the character designated, in combination, means for applying a pronged eyelet clip to the body of an envelop, comprising eyelet riveting mechanism, eyelet clip feed mechanism consisting of a channel for delivering eyelet clips to 90 said riveting mechanism, and escapement mechanism arranged in connection therewith to cut off and deliver the lowest clip in the channel while supporting those above, said escapement comprising a two pointed 95 check lever which is oscillated automatically through the medium of an elastic resilient connection with a positively operated part of the apparatus, said escapement check lever being also adapted for manual 100 manipulation, and which also may be operated manually without interfering with the normal operation of the apparatus.

6. In apparatus of the character designated, in combination, means for applying a pronged eyelet clip to the body of an envelop, comprising eyelet riveting mechanism with eyelet upsetting dies, eyelet clip feed mechanism consisting of a channel for delivering clips to 105 said eyelet riveting mechanism, clip escapement mechanism, a clip rest seat at the bottom of the said channel adapted to receive a clip prong and to centralize the eyelet of the clip with relation to the eyelet upsetting dies, and hinged 110 gates at the bottom of the channel, the front edges of which gates when closed overlap the eyelet flange but which yield before the advance stroke of the riveting punch to allow the clip to pass to the upsetting die.

7. In apparatus of the character designated, in combination, means for applying a pronged eyelet clip to the body of an envelop, comprising eyelet riveting mechanism, eyelet clip feeding mechanism consisting of a channel for delivering clips to 115

said eyelet riveting mechanism, clip escapement mechanism, and pivotally supported clip retaining gates at the bottom of said channel, the front edges of which gates 5 overlap the flange of a clip eyelet positioned at the bottom of the channel of which they form a part, said gates being held in normal position by elastic resilient pressure which allows them to yield to the advance of the 10 riveting punch, as set forth.

8. In apparatus of the character designated, in combination, means for applying a pronged eyelet clip to the body of an envelop, comprising eyelet riveting mechanism, eyelet clip feeding mechanism consisting of a channel for delivering clips to said eyelet riveting mechanism, clip escapement mechanism, and pivotally supported clip retaining gates at the bottom of said channel, 15 the front edges of which gates overlap the flange of a clip eyelet positioned at the bottom of the channel of which they form a part, said gates being held in normal position by elastic resilient pressure which allows them to yield to the advance of the riveting punch, said pivotally supported gates 20 being also formed with rearwardly projecting handle levers by which they may be 25 allowed to yield to the advance of the riveting punch, said relief gates being also formed with handles by which they may be

manipulated manually, for the purpose set forth.

9. In apparatus of the character designated, in combination, means for applying a pronged eyelet clip to the body of an envelop, comprising eyelet riveting mechanism, eyelet clip feeding mechanism consisting of a channel for delivering clips to said eyelet riveting mechanism, clip escapement mechanism, and pivotally supported clip retaining gates at the bottom of said channel, the front edges of which gates overlap the flange of a clip eyelet positioned at the bottom of the channel of which they form a part, said gates being held in normal position by elastic resilient pressure which allows them to yield to the advance of the riveting punch, said pivotally supported gates 40 being also formed with rearwardly projecting handle levers by which they may be manipulated manually, for the purpose described. 45
